Attorney

UNITED STATES PATENT OFFICE.

PAUL MISPEL, OF WEST NEW YORK, NEW JERSEY.

TOY BOMB.

1,315,851.

Specification of Letters Patent.

Patented Sept. 9, 1919.

Application filed November 14, 1918. Serial No. 262,566.

To all whom it may concern:

Be it known that I, PAUL MISPEL, a citizen of the United States, residing at West New York, in the county of Hudson and 5 State of New Jersey, have invented new and useful Improvements in Toy Bombs, of which the following is a specification.

This invention has reference generally to improvements in that class of inventions 10 known as games and toys, and more particularly relates to a toy bomb.

It is the principal aim and object of the present invention to provide a device of the above mentioned character designed so 15 that when dropped upon the ground a loud noise will be made to imitate the explosion of a bomb.

It is an equally important object of this invention to provide a device of the above 20 mentioned character wherein the body is in the form of a rubber cup over which is adapted to be clamped a piece of paper so that when the device is dropped, the air within the cup will be compressed for assuring of the breaking of the piece of paper, thus producing the sound.

As a more specific object the invention consists in the provision of a device of the above mentioned character wherein improved means is employed for removably 25 clamping a piece of paper over the cup; to provide means for rendering the cup air tight when the paper is in position; and to improve the construction of the several 30 parts.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination 45 of elements and the arrangement of parts which will be amplified in the construction hereinafter described and the scope of the application of which will be indicated in the appended claims.

50 The invention is clearly illustrated in the accompanying drawings, in which:—

Figure 1 is a side elevation thereof.

Fig. 2 is a vertical sectional view of the device.

55 Fig. 3 is a top plan view thereof.

Fig. 4 is a detail view.

Similar characters of reference are employed in all of the above described views, to indicate corresponding parts.

Referring now, more particularly, to the accompanying drawings there is provided a handle 1, one end of which is provided with a socket 2 for receiving the inner end of arms 3. These arms are offset to form divergent inclined portions 4, while the outer portions 5 continue from the inclined portions which are arranged in spaced parallel relation with respect to each other. A ring or band 6 is now employed and is formed with suitably spaced openings for engagement with the outer terminals of the arms which terminals are riveted as at 7 to the band or ring 6. Another band or ring 8 is now employed and has its inner edge inclined as at 9, while seated on the inclined edge and the upper edge of this band 8 is the outwardly flared upper edge 10 of a rubber cup 11. Suitable fasteners 12, preferably screws are now employed for fastening the band 8 and the cup 9 to the band or ring 6. A flexible gasket 13 desirably of rubber and of annular conformation is formed with suitable spaced openings and slidably engaged through the medium of these openings on the outer portions 5 of the arms, being disposed so as to seat against the upper surface of the ring or band 6. A clamping metallic band 14 is formed with suitably spaced openings and slidably engaged through the medium of these portions through the outer portions 5 of the arms and above the flexible gasket 13. A sheet of paper 15 is adapted to be disposed between the flexible gasket 13 and the clamping ring or band 14 for assuring of the closing of the open upper end of the cup.

Suitable means for clamping the paper in a taut position across the cup consists of a plurality of cam levers 16 pivotally mounted through the instrumentality of 100 pintles 17 on the outer portions 5 of the arms and it is appreciated that upon swinging of the cam levers the clamping band 14 will move toward the outer ends of the arms for clamping the sheet of paper 15 105 against the flexible gasket which in turn is clamped against the main band 6 and this gasket, of course, assures of the provision of an air tight joint between the cup and the clamping band.

In use, the handle 1 is grasped and the device is thrown on the ground. When the

cup 11 strikes the ground it will be compressed to consequently compress the air therein. This compressed air causes a breaking of the paper for consequently producing 5 a noise designed to resemble a bomb. After the explosion occurs, the cam levers are swung about the pivots to permit of the sliding of the clamping band and enabling the user to place another sheet of paper in position showing that the device may be continuously used.

It is thought in view of the foregoing description that a further detailed description of the operation of the invention is entirely 15 unnecessary. Likewise it is believed that the advantages of the invention will be readily apparent. However, it may be mentioned that the device is particularly adapted to be used on the fourth of July, especially in 20 towns and cities where the use of fire-crackers and other explosives is prohibited.

As many changes could be made in the above construction and many apparently 25 widely different embodiments of this invention could be made without departing from the scope thereof it is intended that all matter contained in the above description or shown in the accompanying drawings shall be interpreted as illustrative and not in a 30 limited sense. It is also to be understood that the language used in the following claims is intended to cover all the generic and specific features of the invention herein

described and all statements of the scope of the invention which as a matter of language 35 might be said to fall therebetween.

What is claimed is:

1. A device of the character described including a handle, arms projecting from one end of the handle, a main supporting band 40 carried by the outer ends of the arms, a rubber cup detachably connected to the band, a sheet of paper adapted to be disposed across the band, a clamping band slidably mounted on the arms, and pivotally mounted cam levers on the upper portions of the arms for moving the clamping band and consequently clamping the sheet of paper in position. 45

2. A device of the character described consisting of a handle, arms extending from one 50 end thereof, a main supporting band carried by the outer ends of the arms, a retaining band, a rubber cup seated on the retaining band, means for securing the retaining band and the cup to the supporting band, a rubber gasket slidable on the outer portions of the arms and seated against the main band, a sheet of paper adapted to be disposed across the rubber gasket, a clamping band slidably mounted on the outer portions of the arms 55 for retaining the sheet of paper, and pivotally mounted cam levers on the outer portions of the arms for removably holding the clamping band in a clamping position. 60

In testimony whereof I affix my signature. 65
PAUL MISPEL.
